UNITED STATES PATENT OFFICE.

JAMES MURPHY, OF SAN ANTONIO, TEXAS.

BENCH-CLAMP.

SPECIFICATION forming part of Letters Patent No. 237,041, dated January 25, 1881.

Application filed October 14, 1880. (Model.)

To all whom it may concern:

Be it known that I, JAMES MURPHY, of San Antonio, in the county of Bexar and State of Texas, have invented a new and Improved 5 Bench-Clamp, of which the following is a specification.

The object of this invention is to provide an improved clamp or tail-screw for carpenters' and cabinet-makers' use, whereby pressure 10 may be brought against the ends of any object to hold it in position on a work-bench.

Figure 1 is a perspective view of the device. Fig. 2 is a side elevation of the same, partly 15 in section, in position on a work-bench.

Similar letters of reference indicate corresponding parts.

In the drawings, A represents the flat metal base-plate provided with a longitudinal groove, a, on its upper face to accomodate the screw- 20 ratchet wheel F. B is a rectangular boss or head, projecting upward from one end of said plate A and provided with a longitudinal screw-threaded perforation, b, for reception of the screw E, and C is the foot forming an integral part of said plate A, or being secured thereto, which foot C is projected straight 25 downward for a short distance and has its toe C' inclined forward, as shown, the face of said toe C' being transversely serrated, as shown 30 at c. A screw, E, having on its front end a block or head, D, and on its rear end a ratchet-wheel, F, is passed through the perforation b in the head B parallel with the face of the plate A.

G is the ratchet-lever, having a forked lower end, the longer prong of which is provided with a slot, f, and having a web, g, between said forks. Said lever G is secured to the rear 35 end of the screw E, with its forked end straddling the ratchet-wheel F by a screw or stud, h, that passes through the slot f into the end 40 of the screw E. The screw E is turned by engaging the web g of the lever G in a radial socket, i, of the wheel F, and then moving the 45 said lever G in one or the other direction, disengaging said web g from the socket i and moving the lever G to engage said web g in another socket, i, renewing the purchase of the lever G at each quarter or half turn of the 50 screw E.

The wheel F is serrated transversely, as

shown at s s, between the sockets i i, to facilitate the operation of the screw E, by hand, up to the point of applying pressure by means of the lever G.

55

H represents a carpenter's bench, provided with sockets m corresponding in shape with the foot C of the clamp.

I represents a dog or stop-block, inserted in one of the sockets m, to serve as a support 60 against which to press or clamp a block of wood or other object, K, that is to be operated upon. The foot C of the clamp or tail-screw A is then inserted in a socket, m, and the screw E turned to bring its head D against 65 the opposite end of the object K and hold it rigidly in position. The inclination of the upper face of the toe C', and the serrations e thereon, engaging against the inclined portion of the socket m, serve to hold said device firmly 70 down in its place.

Being made of iron or other suitable material, this clamp or tail-screw is strong, durable, and inexpensive. It requires no bolts or screws to secure it to the work-bench or other 75 object where its use may be required, and can be put in position and removed easily and quickly. It occupies but little room on account of its compactness, and can be applied to any piece of work without marring it. 80

I do not limit the use of this clamp or tail-screw to the work-bench, as it is designed, also, for general use in shops or other places where the use of clamps is required for cramping up doors, sashes, blinds, and other articles, for 85 which purposes and uses it is eminently adapted, where any suitable piece of scantling or plank is furnished with suitable sockets for its reception.

Having thus fully described my invention, I 90 claim as new and desire to secure by Letters Patent—

The combination, with the grooved plate A, provided with head B and inclined and serrated toe C', of the adjustable screw E, provided with head D, ratchet-wheel F, and ratchet-lever G, substantially as herein shown and described.

JAMES MURPHY.
